FLOYD W. EVANS AND AMANDUS A. MILLER, OF BUFFALO, NEW YORK.

KEROSENE-BURNER.

BEST AVAILABLE COPY

1,394,073.

Specification of Letters Patent.

Patented Oct. 18, 1921.

Application filed September 29, 1920. Serial No. 413,501.

To all whom it may concern:

Be it known that we, FLOYD W. EVANS and AMANDUS A. MILLER, citizens of the United States, residing at Buffalo, in the county of Erie and State of New York, have invented certain new and useful Improvements in Kerosene-Burners, of which the following is a specification.

This invention relates to improvements in kerosene burners and its principal objects are to provide a simply and economically constructed burner available for either domestic or commercial applications and which, with a minimum consumption of kerosene and without liability of back-fire, will give a relatively high pressure of a good fuel mixture with a resultant blue flame of intense strength.

The invention consists in certain features of structure and relation which will be detailed as the description proceeds and, generally speaking, involves the combination of the burner head, the mixing pipe, the air and fuel inlets, and the pipe for conducting a fluid medium heated by the flames from the burner head to a point where said medium raises the temperature of the oil as it enters the mixing pipe.

In the accompanying drawing:

Fig. 1 is a perspective view of an oil burner in which the features of the invention are incorporated.

Fig. 2 is a longitudinal section of the same.

Fig. 3 is a section on the line 3—3 of Fig. 2.

Similar characters of reference designate corresponding parts throughout the several views.

The burner head 1 is hollow and may be of any suitable form and extent. As shown it is rectangular and its sides are extended downward to provide supporting flanges 2. The head 1 on its upper side is provided with burner nipples 3. These are preferably formed as truncated cones and are arranged in close association substantially throughout the area of the top of the head; the nipples 3 are provided with axial ducts communicating with the interior of the head 1.

The fuel mixture is supplied to the head 1 by a conducting pipe 4 which extends over and somewhat close to said head and communicates therewith at a suitable point; thereby the pipe 4 is in the path or zone of

the flames, and the mixture which flows through said pipe is maintained in gaseous state with its constituents thoroughly commingled. The pipe 4 is, in fact, an elongated mixing chamber and in this capacity is connected both with an oil and with an air supply, the points of connection being located beyond the flames and remote from the point at which said pipe is connected to the burner head. The oil may be maintained in an elevated tank (not shown) from which it flows by gravity under the control of a suitable valve (also not shown) as is well known in the art. The oil is conducted by a pipe 5 to the aforesaid mixing chamber constituted by the pipe 4. The fuel mixture is partly completed by air which is supplied under suitable pressure, *i. e.* from one to five pounds, from a tank or storage reservoir (not shown) through a pipe 6; said pipe has its outlet controlled by a suitable valve 7, preferably a needle valve, and beyond and in continuation of said outlet is provided with an attenuated nozzle 8 which projects into the end of the pipe 4, across and beyond the outlet of the pipe 5. The end of the pipe 4 through which the nozzle 8 projects is suitably packed or sealed. The air issues with considerable velocity from the nozzle 8 and takes up the oil supplied by the pipe 5, the mixture flowing throughout the length of the pipe 4 in which it is subject to the heat of the flames. The air which issues from the pipe 8 effects the thorough atomization of the oil and insures the complete formation and gasification of the mixture in the pipe 4.

The fuel mixture is made readily gassifiable by utilizing a fluid medium heated by the flames from the burner head to raise the temperature of the oil as it enters the mixing pipe 4. In the construction shown and preferred this result is accomplished and the fuel mixture is completed by an additional supply of heated air which enters the pipe 4 at the same point as the oil supplied by the pipe 5 and back of the discharge end of the nozzle 7, the latter preferably being thin-walled whereby it may transmit heat to the air within it. Such heated air is supplied by a pipe 9 which is connected to and projects at an angle from the pipe 5. The pipe 9 extends over the flames so as to be subject to the heat thereof and is provided with a down-turned end through which the heated air enters. The

- flow of heated air through the pipe 9 is induced or quickened by the suction influence of the air escaping from the nozzle 8, the action being similar to that of an injector.
- 5 The air which enters the pipe 5 from the pipe 9 heats the oil flowing through said pipe, liberating some of its more volatile components, and thus facilitates the complete atomization of the oil by the escaping 10 from the nozzle 8 and the ultimate complete gasification of the mixture in the pipe 4.

The initial heating of the mixture may be effected in any suitable way, for example, by a priming jet or an electric coil (not shown) 15 suitably arranged in relation to the nozzle 8 and the portion of the pipe 4 surrounding said nozzle, similar to the arrangement in common use for heating flowing currents of liquid or gas.

20 Having fully described our invention we claim:

1. In a kerosene burner, in combination, a hollow burner head having burner ducts, a mixing pipe arranged over and communicating 25 with said head, a pipe for air under pressure having a nozzle communicating with said mixing pipe, an oil pipe communicating with said mixing pipe behind said nozzle, and a pipe for conducting a fluid medium 30 heated by the flames from said burner head to a point back of said nozzle where it raises the temperature of the oil as it enters said mixing pipe.

2. In a kerosene burner, in combination, a hollow burner head having burner ducts, a mixing pipe arranged over and communicating 35 with said head, a pipe for air under pressure having a nozzle communicating with said mixing pipe, an oil pipe communicating 40 with said mixing pipe behind said nozzle, and a pipe for conducting air heated by the flames from said burner head to said mixing pipe at a point back of said nozzle where it raises the temperature of the oil as 45 it enters said mixing pipe.

3. In a kerosene burner, in combination, a hollow burner head having burner ducts, a mixing pipe arranged over and communicating 50 with said head, a pipe for air under pressure having a nozzle communicating with said mixing pipe, an oil pipe communicating with said mixing pipe behind said nozzle, and a pipe overhanging said burner head for 55 taking heated air from above the flames and conducting it to said mixing pipe at a point back of said nozzle where it raises the temperature of the oil as it enters said mixing pipe.

4. In a kerosene burner, in combination, a hollow burner head having burner ducts, a mixing pipe arranged over and communicat-

ing with said head, a pipe for air under pressure having a nozzle communicating with said mixing pipe, an oil pipe communicating with said mixing pipe behind said nozzle 65 and a pipe communicating with and extending at an angle from said oil pipe in overhanging relation to the burner head to convey heated air from above the flames to said oil pipe at a point where it raises the temperature of the oil as it enters said mixing pipe.

5. In a kerosene burner, in combination, a burner head, a mixing pipe extending over and connected to the burner head, an oil supply pipe communicating with the mixing pipe, means for supplying air under pressure to the mixing pipe, and a pipe open to the atmosphere and having the air column therein subject to the suction influence created by the escape of air under pressure into said mixing pipe, said last named pipe being arranged to pass air heated by the flames to said mixing pipe.

6. In a kerosene burner, in combination, a burner head, a mixing pipe connected to said burner head, an oil supply pipe communicating with the mixing pipe, means for supplying air under pressure to the mixing pipe, and a pipe open to the atmosphere and having the air column therein subject to the suction influence created by the escape of air under pressure into said mixing pipe, said last named pipe being arranged to pass air heated by the flames to the mixing pipe.

7. In a kerosene burner, in combination, a burner head, a mixing pipe connected to the burner head, an oil supply pipe communicating with the mixing pipe, means for supplying air under pressure to the mixing pipe, and a pipe open to the atmosphere and extending over the burner head with its open end down-turned to take air from above the flames, said last named pipe having its air column subject to the suction influence created by the escape of air under pressure into said mixing pipe and passing heated air into said mixing pipe.

8. In a kerosene burner, in combination, a burner head, a mixing pipe extending over and connected to the burner head, an oil supply pipe communicating with the mixing pipe, means for supplying air under pressure to the mixing pipe, and a pipe for conducting a fluid medium heated by the flames from said burner head to a point where it raises the temperature of the oil as it enters said mixing pipe.

In testimony whereof we affix our signatures.

FLOYD W. EVANS.
